UNITED STATES PATENT OFFICE.

IRVING M. SCOTT, OF SAN FRANCISCO, CALIFORNIA.

PILLOW-BLOCK FOR SHAFTS.

SPECIFICATION forming part of Letters Patent No. 244,489, dated July 19, 1881.

Application filed May 19, 1881. (No model.)

To all whom it may concern:

Be it known that I, IRVING M. SCOTT, of the city and county of San Francisco, State of California, have invented an Improvement in Pillow-Blocks for Shafts; and I hereby declare the following to be a full, clear, and exact description thereof.

My invention relates to certain improvements in pillow-blocks for heavy shafting; and it consists in a novel method of adjusting and regulating the set of the bearing-brasses by the use of horizontally-inclined wedges and faces with suitable actuating-screws, all operating independently of the cap, which may thus be removed without disturbing the brasses or the set of the shaft, as will be more fully explained by reference to the accompanying drawings, in which—

Figure 1 is a vertical section transverse to the axle. Fig. 2 is a horizontal section. Fig. 3 is a perspective view of one of the side brasses.

A is the base of the pillow-block, which is made of proper form and strength, and having bolt-holes through the extension of the base, so that it may be properly secured in place.

B is the cap, and C is the lower brass, upon which the shaft rests.

D D are the side brasses, which are made to adjust to or from the shaft, and these, with the cap and bottom brass, form the entire box within which the shaft rotates.

This class of bearings are employed for heavy shafts; and in order to adjust the side brasses for wear or for other cause, it is customary to form vertical inclines upon the backs of the brasses, and wedges are fitted to move vertically up and down in a space behind the brasses to adjust them to or from the shaft, as may be required. The objection to this method is that the wedges must necessarily be short, (being limited by the depth of the side brasses,) and their bearings are so small that the brasses are liable to twist on this account. They can also have but a short space for adjustment, and, lastly, as they must be adjusted by screws which pass through the cap, these must be removed before the cap can be taken off, thus leaving the brasses unsupported, and the set of the shaft may thus be disturbed by the removal of its side supports.

In my invention the side brasses, D, have flanges E projecting at right angles from the ends, so as to fit the sides of the pillow-block, and thus hold the brasses in place, as shown. The backs of the brasses are formed in with an incline face, F, extending from end to end of the brass between the flanges. Wedges G are fitted into the space behind the brasses, lying horizontally and having holes formed in their ends with screw-threads to receive the horizontal screws H, which, when turned, will cause the wedges to advance or recede. The shanks of the screws have collars I, which fit in spaces between the flanges E of the brasses and a projection, J, so that when turned the screw will not advance or recede, but will move the wedge. Instead of forming screw-threads in the ends of the wedges, as above described, recesses may be made to receive nuts which will operate in the same manner. These wedges may be made of considerable length, on account of the width of the box, and they will thus support the brass for so great a distance that it will be very rigid and will not twist or get out of place. The space for adjustment is much longer, and, finally, as the adjusting-screws pass in through the sides and are independent of the cap, the latter may be removed for inspection or other purposes without touching these screws or in any way disturbing the position of the brasses or the set of the shaft, which might otherwise get out of place.

Having thus described my invention, what I claim as new, and desire to secure by Letters Patent, is—

The improvement in pillow-blocks, consisting of the brasses D, arranged at each horizontal side of the journal, and having the horizontally inclined or tapering backs F, in combination with the horizontally-moving wedges G, and the operating-screws H, substantially as and for the purpose set forth.

In witness whereof I have hereunto set my hand.

IRVING M. SCOTT.
